UNITED STATES PATENT OFFICE.

JULIUS INGALSBE, OF BASOM, NEW YORK.

FASTENER FOR COVERS OF PAILS.

1,103,208.

Specification of Letters Patent. Patented July 14, 1914.

Application filed April 7, 1913. Serial No. 759,510.

To all whom it may concern:

Be it known that I, JULIUS INGALSBE, a citizen of the United States, residing at Basom, in the county of Genesee and State 5 of New York, have invented certain new and useful Improvements in Fasteners for Covers of Pails, of which the following is a specification, reference being had to the accompanying drawings.

10 This invention relates to certain improvements for fasteners for covers of pails or the like and has for its object to provide a device of this general character having novel and improved means whereby the cover is 15 effectively maintained in closed position and which may be operated with convenience and facility.

The invention consists in the details of construction and in the combination and arrangement of the several parts of my improved fastener whereby certain important advantages are attained and the device is rendered simpler, less expensive, and otherwise more convenient and advantageous for 25 use, all as will be hereinafter more fully set forth.

The novel features of the invention will be carefully described in the appended claim.

In order that my invention may be the better understood, I will now proceed to describe the same with reference to the accompanying drawings wherein—

Figure 1 is a front elevation of my improved pail showing the lid or closure therefor in raised position and disclosing parts of the pail proper broken away. Fig. 2 is a plan view of the pail. Fig. 3 is a section therethrough as seen on line 3—3, Fig. 2. Fig. 4 is a similar view as seen on line 4—4, Fig. 2. Fig. 5 is an enlarged detail section through the locking means of the top; and Fig. 6 is a similar view taken on a plane at right angles to the plane of Fig. 5.

As disclosed in the accompanying drawings 45 1 denotes a pail of a character especially adapted for use for holding live bait and includes the top plate or wall 5 provided with a suitable opening for entrance within the pail, and as herein disclosed such opening is 50 adapted to be closed by the cover 7 hingedly engaged with the top wall or plate 5 as indicated at 2 on the accompanying drawing, said cover being herein shown as provided with a depending flange 8 adapted to project

through the opening for a purpose which is 55 believed to be self-evident. I have provided an improved means for locking this cover and to this end, the same is depressed about centrally, as shown at 9 and provided with a longitudinal slot 10. The side walls of this 60 depression 9 are inclined inwardly toward one another and the under face of the closure 7 is provided with a wear plate 11. Disposed through this slot 10 is a lug 12, the head portion of which is beveled along the 65 side edges thereof coincident to the inclination of the side walls of said depression 9, so that when fitted closely therein, the upper edge of said lug is below the upper surface of the cover 7 and the inner end of said lug 70 12 is secured to a sliding bolt 13 which is guided through an opening 14 in the flange 8 of the cover 7. A keeper 15 is carried by the under face of the top wall 5 to receive the free end of said sliding bolt therein when 75 the cover is in its lowered position and said bolt is effectively disposed and also carried on the lug 12 between the sliding bolt thereon and the under face of the closure, is a leaf spring 16. This leaf spring is bent and the 80 free end thereof is adapted to contact with the wear plate 11 and through the friction of the spring against the wear plate, said sliding bolt is adapted to be securely held in any adjusted position.

85 From the foregoing description, it is thought to be obvious that a fastener for the cover of a pail constructed in accordance with an embodiment of my invention is of an extremely simple and comparatively inexpensive nature and is particularly well adapted for use by reason of the convenience and facility with which it may be assembled and it will also be obvious that my invention is susceptible of some change and modification without material departure from the spirit and scope thereof and for this reason I do not wish to be understood as limiting myself to the precise arrangement and formation of the several parts herein shown in 90 carrying out my invention in practice except as is defined by the appended claim.

95 Having thus described this invention, what is claimed is:

100 A device of the character described comprising a pail having an opening in its top, a hinged cover for said opening, said cover being provided with a slot, a keeper carried

by the pail, a finger piece directed through the slot, a locking bar secured to the finger piece and adapted to be engaged with the keeper, and a flat spring interposed between the hinged cover and the locking bar, said spring having one extremity anchored to and movable with the finger piece, the opposite extremity of the spring being in fric-

tional contact with the under surface of the hinged cover.

In testimony whereof I hereunto affix my signature in the presence of two witnesses.

JULIUS INGALSBE.
